UNITED STATES PATENT OFFICE

GEORGE H. PHELPS, OF WAREHOUSE POINT, CONNECTICUT, ASSIGNOR, BY MESNE ASSIGNMENTS, TO AMERICAN RADIATOR & STANDARD SANITARY CORPORATION, A CORPORATION OF DELAWARE

RADIATOR

Application filed October 19, 1929. Serial No. 400,786.

This invention relates to radiators of the type in which heat is conducted by means of radiating vanes from a steam pipe or other source of heat to currents of air passing upwardly over the surfaces of the vanes.

An object of the invention is to provide a radiating vane construction that will economize in the quantity of metal required for the vanes and will utilize this metal in the 10 manner most efficient and effective for the transfer of heat to the air currents.

In a radiator of the above type the cool air comes into contact first with the lower radiating vanes, or lower parts of the vanes, and 15 is heated to progressively higher temperatures in its upward passage in contact with the vanes. If the temperature of the vanes be kept as nearly as possible to the temperature of the heating element, the transfer of 20 heat from the vanes to the air will be much more rapid in the lower vanes, or the lower parts of the vanes, than in the upper parts of the radiator, since the difference in temperature or temperature gradient from the 25 vanes to the air is much greater at those places where the coolest air is in contact with the heated vane.

Inasmuch as more heat is thus abstracted from the vanes at the lower part of the radiator, a larger quantity of heat must be conducted through the vanes at the lower part of the radiator if the outer portions of the vanes are to be maintained at a temperature to obtain the most effective transfer of heat.

30 Further objects of the present invention are, therefore, to provide a radiator having heat transferring vanes of greater heat conducting capacity in the lower part of the radiator than in the upper part, and further, 35 to provide for a greater heat transferring capacity of the lower vanes, or lower portions of the vanes, by increasing the thickness of the heat conducting metal.

Further objects will be apparent from the 40 following description of the invention.

The various features of the invention are illustrated in the accompanying drawings, in which—

Fig. 1 is a vertical front view of a radiator 50 and radiator enclosure, the latter being

broken away in part to show the position and construction of the radiator.

Fig. 2 is a vertical view of the radiator and a section of the enclosure taken at right angles to the view of Fig. 1.

Fig. 3 is a plan or top view of the radiator.

In the present invention a number of vertical heat distributing vanes are mounted on heating elements, preferably horizontal steam or hot water pipes or electric heating elements. The vanes extend transversely to the heating element and the heat is conveyed by conduction from those portions of the vanes in direct contact with the heating element to the parts most distant therefrom. The heat is given up from the vanes and from the heating elements to the air, the heated air rising or being displaced upwardly in the channels or flues between the vanes, thereby setting up a circulation of heated air throughout the room to be heated. The vanes may be either continuous from the lowermost part of the radiator to the uppermost, or may be formed in vertical tiers. The lower parts of the radiators or the lower tiers are made of greater heat conducting capacity or greater thickness than the upper parts or upper tiers, so that the larger quantities of heat that are taken up by the direct contact of the cooler air with the hot vanes may be conducted from the heating element to the outer parts of the vanes without such a drop in temperature as would excessively reduce the heating capacity of the outer portions of the vanes.

In Figs. 1, 2 and 3 of the accompanying drawings the invention is illustrated as applied to a radiator having an upper tier 10 and a lower tier 11 of heat distributing vanes. The vanes of tiers 10 and 11 are mounted on horizontal pipes connected to a continuous 90 conduit by return bends 12.

In the specific example shown, two parallel pipes 13 and 14 are provided in each tier, steam being admitted to these pipes from a common steam header 15. Upon the pipe 14 of the lower tier there are mounted the corrugated plates 16 and 17 to form the lower tier of radiating vanes, having inner areas 18 at which the plates meet in a vertical plane on the pipe 14 and having outwardly extend-

ing areas that form flues at their outer edges and intermediate flues 20 that are open at their outer edges. A pair of corrugated plates 21 and 22 are similarly mounted on the heating pipe 13 and form correspondingly closed and open flues 23 and 24, respectively, the flues 19 and 23 being longitudinally offset so that the open and closed flues alternate. The plates 16, 17, 21 and 22 are made of relatively thick or heavy metal of high heat conductivity, as indicated by the heavy lines in the drawings.

Corrugated plates 25 and 26 and 27 and 28, made of relatively much lighter material and of less heat conducting capacity than the plates 16, 17, 21 and 22, are mounted on the pipes 14 and 13, respectively, of the upper tier and similarly form laterally enclosed air flues 29 and 30 and open sided flues 31 and 32, respectively. The flues 29 and 30 may be positioned to coincide with the flues 19 and 23, respectively, but preferably, as shown in the drawings, are longitudinally offset relatively to each other so that the laterally closed flues 19 are directly beneath the open sided flues 31, and the closed flues 30 are directly above the open sided flues 24, thereby breaking up the air currents and providing a more rapid convection of the heat.

30 The radiator thus formed may be enclosed in a radiator enclosure 33 having an inlet opening 34 at its lower end and an outlet opening or grille 35 through which the heated air is deflected by deflecting plates 36. The 35 radiator structure is supported above the floor by means of supporting legs 37.

The invention may also be applied to a radiator having heat distributing vanes and air channels extending continuously from the 40 lower to the upper part of the radiator, but having the lower part of the vanes of greater thickness than the upper part, or having the thickness of the plates at different latitudes in proportion, approximately, to the amount of 45 heat to be transferred from the heating element to the upwardly passing currents of air. Such a graduation of thickness may be obtained in any suitable manner.

50 The method of forming vertical vanes electrolytically as described in my pending application Serial No. 378,612 filed July 6, 1929, may be employed for this purpose. In using the method of the above application in forming radiator vanes of graduated thickness, 55 the heat conducting metal is deposited electrolytically upon a base of thin sheet metal which may be of iron, steel or brass, and the electrolytic apparatus is so arranged that a thicker deposit is formed in the lower portions of the vanes. The apparatus may also be so arranged, as shown in the above application, that the electrolytic deposits of copper 60 may be thicker in those portions of the vanes nearest the heating element.

65 In the preferred form of the invention,

therefore, the thickness of the heat conducting metal diminishes towards the upper and outer parts of the vanes.

With this construction, the lower parts of the radiator vanes may be made of a thickness adequate to maintain the outer parts of the vanes at the highest practicable temperature so as to obtain the greatest possible heat transfer throughout the entire area of the vanes without increasing the weight and 75 quantity of metal in the upper part of the vanes beyond what is required for heat distribution in the upper areas.

What I claim is:

1. A radiator having a heating element, 80 heat distributing vanes mounted in spaced positions transversely on said heating element, the thickness of said vanes decreasing gradually from one side of said heating element to the other side.

2. A radiator having heating elements, 85 vertical heat distributing vanes mounted in spaced positions on said heating elements, the thickness of said vanes decreasing in an upper and outer direction.

3. A radiator having an upper and a lower horizontal heating element, vertical, 90 spaced heat distributing vanes on said heating elements, the vanes on the upper element being thinner than those of the lower element and the thickness of said vanes decreasing at increasing distances from the heating element.

4. A radiator having an upper and a lower horizontal heating element, vertical, 100 spaced heat distributing vanes on said heating elements, said vanes forming alternately enclosed and open vertical flues, the vanes on the upper element being thinner than those of the lower element and the thickness 105 of said vanes decreasing at increasing distances from the heating element.

5. A radiator having an upper and a lower horizontal heating element, vertical, 110 spaced heat distributing vanes on said heating elements, said vanes forming alternately enclosed and open flues, the vanes on the upper element being thinner than and longitudinally displaced relatively to those of the lower element and the thickness of said 115 vanes decreasing at increasing distances from the heating element.

6. A radiator comprising a pair of spaced upper heating tubes and a pair of lower spaced heating tubes, vertical vanes mounted on the tubes of each of said pairs and forming open and enclosed air flues, the closed flues of one tube alternating with the closed flues of the tube below and to the side of it, the vanes of the upper tubes being of less heat conducting capacity than those of the lower tubes.

In witness whereof, I have hereunto signed my name.

GEORGE H. PHELPS. 130
